United States Patent

Des. 239,704
Patented Apr. 27, 1976

239,704

MICROMETER

Paul A. Morgan, Chicago, Ill., assignor to Century
Wheels Research Corp., Lake Bluff, Ill.

Filed Sept. 27, 1974, Ser. No. 509,815

Term of patent 14 years

Int. Cl. D10—04

U.S. Cl. D10—73

FIG. 2

FIG. 1

FIG. 3

FIG. 4

FIG. 5

FIG. 6

FIG. 8

FIG. 7

FIG. 9

FIG. 10

FIG. 1 is a front elevational view of a micrometer showing my new design.

FIG. 2 is a right side elevational view thereof;

FIG. 3 is a bottom plan view thereof;

FIG. 4 is a rear elevational view thereof;

FIG. 5 is a left side elevational view thereof;

FIG. 6 is a top plan view thereof;

FIG. 7 is a front elevational view of a second embodiment of a micrometer showing my new design of FIG. 1, the micrometer otherwise being substantially identical to that of FIG. 1;

FIG. 8 is a left side elevational view of the micrometer of FIG. 7;

FIG. 9 is a front elevational view of a third embodiment of my new design of FIG. 1, all other views being identical to FIGS. 2-4 and 6;

FIG. 10 is a front elevational view of a fourth embodiment of my new design of FIG. 1, all other views being identical to FIGS. 2-4 and 6.

I claim:

The ornamental design for a micrometer, as shown and described.
